WILLIAM R. THOMAS, OF PHILADELPHIA, PENNSYLVANIA.

SAFETY GAS VALVE.

1,403,351.

Specification of Letters Patent. Patented Jan. 10, 1922.

Application filed October 2, 1920. Serial No. 414,164.

To all whom it may concern:

Be it known that I, WILLIAM T. SMITH, a citizen of the United States, residing at Coatesville, in the county of Chester and 5 State of Pennsylvania, have invented new and useful Improvements in Safety Gas Valves, (Case "A,") of which the following is a specification.

The present invention has reference to improvements in gas burners, and has for its 10 object to provide such burners with means for closing the valves thereof to prevent the passage of gas therethrough, when the light from the burner has been extinguished.

15 A further object is the production of a safety gas burner which shall be of a comparatively simple construction and which will automatically influence the valve thereof to a closed position when the light at the 20 tip of the burner has been extinguished accidentally or otherwise.

25 A further object is the production of a safety gas burner which will be positive in action for automatically influencing the valve therein to a closed position when the 30 gas light has been extinguished.

The foregoing, and other objects which will appear as the nature of the invention is better understood, may be accomplished 35 by a construction, combination and operative arrangement of parts, such as is disclosed by the drawings which accompany and which form part of this application.

In the drawings:—

35 Figure 1 is an elevation of an automatic safety gas burner constructed in accordance with this invention.

40 Figure 2 is a sectional view approximately on the line 2—2 of Figure 1.

45 Figure 3 is a sectional view approximately on the line 3—3 of Figure 2.

Figure 4 is a sectional view approximately 50 on the line 4—4 of Figure 1.

Figures 5 to 8 illustrate details.

45 The body of my improvement is in the nature of a casing and is indicated by the numeral 1. The body may have a longitudinal passage therethrough whose ends are threaded when it is desired that the burner 55 be screwed on the ends of sections in a pipe line through which the gas is conducted. However, the body may only have arranged therein a pocket 2 which enters from one of the ends thereof, and the outer portion of

55 the said pocket is round and provided with interior threads 3 so that the body may be

screwed on the gas conducting pipe. The bottom of the body is preferably provided with a threaded opening 4 which communicates with the pocket 2, the said opening 60 being closed by a threaded plug 5. The plug, on its inner face has a central socket 6 therein the walls of which provide a guide for one end of a stem 7 of a valve 8 which controls the passage of the gas through the 65 pocket to the burner tip. The stem 7 is surrounded by a spring 9 that exerts a tension between the valve 8 and the plug 5 so that the valve is normally retained on its seat 10. The seat is preferably in the nature of 70 a removable member which is threaded in an opening 11 disposed directly opposite the opening 4. The seat also provides a guideway for a stem 12 that projects from the valve in an opposite direction from the 75 stem 7, and this last mentioned stem is provided with a plurality of preferably spirally arranged grooves 13 that provide passages for the gas when the valve is unseated.

Screwed in the opening 11 of the body is 80 a tubular gas burner 14. The burner has, adjacent its outer open end, an inturned flange 15 on which the stone tip 16 of the burner is seated. Communication with the slit which provides the gas passage through 85 the burner tip 16, and secured in the said tip, in any desired or preferred manner, is a gas tube 17. This tube is arranged centrally in the tubular member 14, the latter being in the nature of a jacket which is contacted by split friction rings 18 arranged in grooves 19 on the outer periphery of a cylindrical plunger 20. The upper end of the plunger is centrally provided with an opening for the passage of the gas tube 17, and 90 its lower closed end centrally provided with a gas tube 21 that telescopically receives therein the gas tube 17. The tube 21 is provided with a plurality of openings 22 adjacent to its lower closed end.

100 The plunger member has arranged therein a semi-liquid body 26 which is highly susceptible to expansion from the heat of the burner but which is also highly susceptible to contraction from the cold. Surrounding 105 the fluted or grooved stem 13 of the valve 8, the apertured projecting end of the gas conducting tube, and exerting a pressure between the seat 10 and the hollow plunger 20 is a spring 27.

110 Having a yoked end which is freely received in a groove in the widened upper por-

tion of the lower stem 7 of the valve 8 is an arm 28. This arm is centrally connected to a shaft 29 that has one of its ends journaled in one of the walls of the pocket 2 and its 5 other end projecting through a stuffing box 30 in the opposite end of the body that communicates with the pocket. The last mentioned end of the shaft has an angular extension 31 to which is connected a pull chain 10 32. It will be apparent that when a pull is exerted on the chain the shaft will be turned so that the forked arm thereof will be swung downwardly in the pocket 2 causing the valve 8 to be unseated. On the side of the 15 body through which the shaft extends there is secured for slidable movement in a bracket 33 a spring influenced pin 34. This pin is designed to be received through one of the links of the chain 32 and hold the valve unseated, so that the gas will flow through the 20 pocket 2 of the burner, through the spiral grooves in the upper stem of the valve, through the openings in the lower gas tube, and through the upper gas tube. This permits of the gas being ignited. The gas soon 25 heats the tip 16 and the jacket 14, so that the fluid 26 in the member which I have termed the plunger will be expanded, which causes the lower closed end of the gas tube 30 connected with the plunger to contact with the upper stem of the valve, moving the valve still further away from its seat. As long as the fluid is expanded, thus forcing 35 downwardly the plunger to engage the valve stem, the valve will be held unseated. The gas can be extinguished by again operating the shaft to close the valve, or should the gas be accidentally extinguished, the fluid in the plunger will be immediately contracted 40 which permits of the spring 27 to move the same upward in the direction of the tip, allowing the spring 9 to again hold the valve seated.

Having thus described the invention, what 45 I claim, is:—

1. In a device of the class described, in combination with a casing, of a tubular gas burner extending upwardly from the casing, a gas tip therefor, a cylindrical plunger disposed in said burner, a gas delivery tube extending through the plunger, having a plurality of apertures formed therein and provided with a lower closed end, a tube secured to said tip and extending into the upper end 50 of the first mentioned tube, a valve in said casing having a stem extending into the burner adjacent to the plunger, expansive matter in the plunger adapted to move the same into valve contacting position, spring means to return the plunger to normally inoperative position upon contraction of the expansive matter, and independent spring means to normally retain the valve seated when the flame is extinguished.

2. In an automatic gas extinguisher, a 65 casing, a valve controlling the passage of gas in said casing, a tubular gas burner extending upwardly from the casing, a tip for said burner, a gas delivery tube projecting inwardly from said tip, a cylindrical plunger 70 disposed in said burner, a tube telescopically receiving the lower end of the first mentioned tube, extending through the bottom of said plunger, having a plurality of apertures formed therein and provided with a 75 lower closed end, friction rings arranged on the outer periphery of said plunger, spring means to retain the plunger in its normal inoperative position, expansive matter in the plunger adapted to move the same 80 against the tension of its spring, spring means to return the valve to its normal seated position upon contraction of the expansive matter, valve actuating means projecting through the casing for regulating the 85 initial flow of gas and latching means therefor to cause the valve aforesaid to remain unseated until contact with said plunger is consummated.

3. In a device of the class described, in combination with a casing, of a tubular gas burner extending upwardly from the casing, having an annular flange integrally formed adjacent the end thereof and projecting inwardly, a stone tip for the burner seated on 90 the flange, a gas delivery tube projecting inwardly from said tip, a cylindrical plunger disposed in said burner, a tube telescopically receiving the gas tube, extending through the bottom of said plunger, having 95 a plurality of apertures formed therein and provided with a lower closed end, friction rings arranged on the outer periphery of said plunger, a valve seat in said casing, spring means extending from the upper surface thereof to retain the plunger in 100 normal inoperative position, a valve having a 105 grooved stem projecting into the burner, the end thereof being adjacent to the closed end of the plunger, expansive matter in the plunger adapted to move the same against the tension of its spring into engagement with 110 said valve stem to unseat the valve and cause the same to remain open while the burner is subjected to the action of heat, said 115 expansive matter also susceptible to contraction when the flame from the gas is extinguished to permit of the spring means seated in the base of the casing to retain the valve normally seated, means projecting 120 through the casing for operating said valve against the tension of its spring, and latching means for the valve opening means to hold the valve unseated until the plunger engages the valve stem and regulates the 125 same after the burner is lighted.

In testimony whereof I affix my signature.

WILLIAM T. SMITH.
